UNITED STATES PATENT OFFICE.

GEORGE S. BENNETT, OF SAN FRANCISCO, CALIFORNIA, ASSIGNOR TO
OSCAR C. HAMLET AND DANIEL P. FOLEY, OF SAN FRANCISCO, CALI-
FORNIA.

GAS-REGULATOR.

SPECIFICATION forming part of Letters Patent No. 728,153, dated May 12, 1903.

Application filed September 13, 1902. Serial No. 123,305. (No model.)

To all whom it may concern:

Be it known that I, GEORGE S. BENNETT, a citizen of the United States, residing at San Francisco, in the county of San Francisco and 5 State of California, have invented a new and useful Gas-Regulator, of which the following is a specification.

This invention relates to gas-regulators.

The object of the invention is to simplify 10 the construction and increase the efficiency of devices of this character whereby they are rendered more sensitive in operation and are adapted to control the flow of gas in a certain and positive manner irrespective of its pressure. 15

A further object is to construct the regulator in such manner that the valve may be adjusted from the exterior without necessitating disconnection of the regulator from the 20 pipes after it is once installed.

A further object is to insure proper operation 25 of the valve whether the regulator be plumb or not.

With these and other objects in view, as 30 will appear as the nature of the invention is better understood, the same consists of the novel construction and combination of parts of a gas-regulator, as will be hereinafter fully described and claimed.

In the accompanying drawings, forming a 35 part of this specification, and in which like numerals of reference indicate corresponding parts, there are illustrated two forms of embodiment of the invention each capable of carrying the same into practical operation, it being understood that the elements therein exhibited may be varied or changed as to shape, proportion, and exact manner of assemblage without departing from the spirit thereof.

In the drawings, Figure 1 is a view in vertical section through a gas-regulator embodying the essential features of the present invention. Fig. 2 is a similar view of a slightly modified form. Fig. 3 is a horizontal sec-

40 tional view taken on the line 3-3, Fig. 1. Fig. 4 is a similar view taken on the line 4-4, Fig. 2. Fig. 5 is a horizontal sectional view taken on the line 5-5, Fig. 2. Fig. 6 is a detached detail view of the valve shown in Fig. 1. Fig. 45 7 is a collective detail view showing the man-

ner in which the valve of the regulator shown in Fig. 1 may be adjusted. Fig. 8 is a detached detail view of a key or wrench for adjusting the valve shown in Fig. 2.

Referring to the drawings, and to Figs. 1, 55 3, 6, and 7, 1 designates the casing of the regulator, the lower end of which is threaded for connection with the inlet-pipe 2, one side of the casing having an internally-threaded extension 3 for connection with the outlet-pipe 4. As the two pipes may be of common or any preferred construction and as they perform the usual function, further description is deemed unnecessary. The upper portion of the casing has arranged within it an inverted cup 5, which may be either integral with the casing or secured thereto and is spaced a sufficient distance from the inner walls thereof to present a chamber 6, in which works a float 7, the chamber containing mercury to present an effective seal. The top 8 of the cup is inset from its upper end to present a chamber or space to contain a body of gas to constitute a cushion for the float, said top being provided with a plurality 75 of orifices 9, through which gas escapes beneath the float, and with a central orifice 10, through which projects the upper portion of a float-rod 11, which latter is secured to the float in any preferred manner, preferably by the 80 employment of two nuts 12, turned on a threaded length of the rod and bearing, respectively, against the upper and under faces of the top of the float. The upper end of the rod is squared for engagement by a key when 85 adjustment of the valve is necessary, as will presently appear. The valve 13 (shown in detail in Fig. 6) is a truncated cone, preferably dished beneath, and is provided in this instance with four radial arms 14, constituting 90 guides to coact with the walls of the bore of the casing to cause the valve to be maintained in operative position without interference with its freedom of action, the arrangement being such that the valve will be held against 95 swaying, even though the regulator be tilted or be out of plumb. The lower portion of the valve coacts with a tapered valve-seat 15, formed in the lower portion of the casing, the space between the periphery of the valve and 100

the walls of the seat constituting a passage-way for the gas. The valve has associated with it by a threaded connection 16 the lower end of the float-rod 11, which upon being turned will operate to raise and lower the valve to effect requisite adjustments. The lower portion of the valve carries a bifurcated extension 18, which is adapted to straddle a cross-bar 19, arranged at the bottom of the casing, the said bar operating to prevent the valve from turning when the same is being adjusted to adapt it to the pressure of gas passing through the regulator. Disposed on the top of the float are a plurality of weights 20, which are provided for the purpose of balancing the float, according to the pressure and supply of gas required, as is usual with devices of this character. It is a desideratum to obviate disturbing the weights when once installed; but with regulators in common use this is necessary. Both the disconnection of the casing from the pipe and the removal of the weights are obviated in the present device in a simple and thoroughly-effective manner and is accomplished by providing the casing with a detachable cap or cover 21, which may be associated therewith in any preferred manner, in this instance by providing the outer surface of its lower end with a circumferential channel 22 to be engaged by headed studs 23, projecting inward from the top of the casing, communication with the channel being effected through two alined recesses 24, cut in the under side of the cap and communicating with the channel. When it is desired to adjust the valve, the cap is turned until the recesses 24 are opposite the studs 23, when it may be removed. A key 25 (shown in detail in Fig. 7) is then seated on the squared terminal 26 of the float-rod and upon being turned rotates the float and with it the rod 11, and as the valve is held from rotation through the coaction between the bifurcated extension 18 and the bar 19 it follows that the valve must be raised or lowered, according to the direction in which the float-rod is turned. By the arrangements shown the valve can be adjusted to render it sensitive and positive in operation no matter what the pressure of the gas may be. By preference the valve is made of aluminium in order to avoid rust with consequent danger of binding.

In the form of embodiment of the invention shown in Figs. 2, 4, 5, and 8 the main difference resides in the manner of adjusting the valve and in the manner of holding it against turning while being adjusted. In this arrangement the casing is provided with two inward-projecting guides 27, in which work rods 28, carried by two alined radial arms 14, as clearly shown in Fig. 5. It will be seen that this arrangement will be thoroughly efficient in holding the valve against turning. The top of the cup 29 is inset for the same purpose as that described in connection with Fig. 1 and is provided with a central orifice 30, which performs the double

function of a means for supplying gas beneath the float and also as a passage-way for the float-rod 11. The top 31 of the float is provided with two sockets or openings 32 to be engaged by prongs 33 of a key 34, (shown in detail in Fig. 8,) and in order that the key may be brought into engagement with the sockets it will be necessary to remove the weights 20. The cap 21 is associated with the casing in the same manner as that shown in connection with Fig. 1. In operation the device shown in Fig. 2 is as effective in every particular as that shown in Fig. 1, and both devices will in a thoroughly reliable manner fulfil all of the requirements demanded of devices of this character.

While the construction and arrangements herein shown are illustrative of two operative devices, it is to be understood that the invention is not to be limited to the exact details shown as the different parts may be changed as to shape and proportion and still be within the scope of the invention.

Having thus fully described my invention, what I claim is—

1. A gas-regulator having a vertically-adjustable valve, means for holding said valve against rotation, and a rotatable float connected therewith.

2. A gas-regulator comprising a valve, means for holding it against rotation, a rotatable float, and a rod rigid with the float and having a threaded connection with the valve.

3. In a gas-regulator, a valve, means for holding it against rotation, a float, a rod connecting the valve and the float and projecting above the latter and provided with means to be operated by a key to effect adjustment of the valve.

4. In a gas-regulator, a valve, means for holding it against rotation, a float, a rod connecting the valve and the float and projecting above the latter and provided with a squared terminal to be engaged by a key to effect adjustment of the valve.

5. In a gas-regulator, the combination with a casing, of a valve, means for holding it against rotation, a float, a rod connecting the valve and the float and projecting above the latter and provided with a squared terminal, and a cap detachably associated with the upper portion of the casing to allow access to the terminal of the rod to effect adjustment of the valve.

6. In a gas-regulator, the combination with a casing, of an inverted cup spaced from the sides of the casing to present a mercury-chamber, the top of the cup being provided with openings, a valve, means for holding said valve against rotation, a float arranged in said chamber, and a rod rigid with the float and having a threaded connection with the valve.

7. In a gas-regulator, the combination with a casing, of an inverted cup spaced from the sides of the casing to present a mercury-

chamber, the top of the cup being inset from its upper end and provided with openings, a valve, means for holding said valve against rotation, a float arranged in said chamber, 5 and a rod rigid with the float and having a threaded connection with the valve.

In testimony that I claim the foregoing as

my own I have hereto affixed my signature in the presence of two witnesses.

GEORGE S. BENNETT.
